US00D745881S

(12) **United States Design Patent**
Ray et al.

(10) **Patent No.:** **US D745,881 S**
(45) **Date of Patent:** ** *Dec. 22, 2015

(54) **DISPLAY SCREEN WITH GRAPHICAL USER INTERFACE**

(71) Applicant: **Microsoft Corporation**, Redmond, WA (US)

(72) Inventors: **Ethan Nelson Ray**, Lynnwood, WA (US); **Leslie MacNeil**, Kirkland, WA (US); **Jonathan Eric Gleasman**, Seattle, WA (US); **Denise Michele Trabona**, Seattle, WA (US)

(73) Assignee: **Microsoft Corporation**, Redmond, WA (US)

(*) Notice: This patent is subject to a terminal disclaimer.

(**) Term: **14 Years**

(21) Appl. No.: **29/449,717**

(22) Filed: **Mar. 15, 2013**

(57) **CLAIM**

The ornamental design for a display screen with graphical user interface, as shown and described.

DESCRIPTION

The single FIGURE is a front view of a display screen with graphical user interface showing the new design.

The broken line showing of the display screen and square shape are for environmental purposes only and forms no part of the claimed design.

1 Claim, 1 Drawing Sheet
